UNITED STATES PATENT OFFICE

ROGER ADAMS, OF URBANA, ILLINOIS, ASSIGNOR TO ABBOTT LABORATORIES, OF NORTH CHICAGO, ILLINOIS, A CORPORATION OF ILLINOIS

BACTERICIDE APPLICABLE TO ACID-FAST BACTERIA

No Drawing.

Application filed December 28, 1928. Serial No. 329,077.

This invention relates to the preparation of aliphatic acids and derivatives of these acids. These compounds have the general formula

where R and R' represent aliphatic hydrocarbon radicals such as alkyl or alkylene, and where Z represents a hydrogen atom, an alkali or alkaline earth metal or a hydrocarbon radical.

Chaulmoogra oil, chaulmoogric acid, and homologues of chaulmoogric acid and their derivatives have long been known to be effective in combating certain diseases such as leprosy, produced by acid-fast bacteria. Such chaulmoogra derivatives contain an unsaturated five membered carbon ring to which the activity against the leper bacilli was formerly attributed. Recent discoveries have shown that a variety of other acids which contain other types of carbon rings are also effective against such acid-fast bacteria.

My further discoveries seem to demonstrate that a ring structure is not necessary but that the number of carbon atoms, the molecular weight of the compounds, and the position of the carboxyl group in the chain, are the important factors in determining the bactericidal and bacteriostatic efficiency of the products. (The term "bacteriostatic" means "preventing growth of bacteria", as distinguished from "bactericidal" which means "bacteria destroying".) Compounds containing more than nine and less than twenty-two carbon atoms appear to be most efficient, particularly those containing 15 to 18 carbon atoms. The presence or absence of a ring structure seems to be of minor importance.

The discovery of the bactericidal efficiency of these acids described in this application is of particular importance since certain analogous compounds, which are very well known, such as stearic acid, show no appreciable germicidal efficiency whatsoever. In stearic acid, the carboxyl group is at the end of the chain of seventeen carbon atoms. I

have found that if the carboxyl group is removed from this position, and placed farther down towards the center of the chain, the efficiency is markedly increased. The highest efficiency seems to reside in such compounds in which the carboxyl group is attached to the middle carbon atom or to a carbon atom that is near the middle.

These acids have the additional advantage that they may be prepared and made available for therapeutic use much more readily than is the case with the ring containing compounds previously studied.

These acids may be prepared by introducing the hydrocarbon radicals successively into an ester with an active methylene group, which then on treatment with alkalies, can yield a substituted acetic acid. Examples of such esters are malonic ester and acetoacetic ester. Illustrating with malonic ester, the reactions involved are as follows, where R and R' are aliphatic alkyl radicals, such as alkyl or alkylene:—

The following examples of such acids and some of their intermediates from which they are prepared are given as illustrations of the

invention. Unless otherwise indicated in the formula, the hydrocarbon radicals are straight chains. Wherever two formulae are given, the first mentioned formula refers to 5 the intermediate diethyl dialkyl malonates.

As an example, ethyl di-n-heptyl acetate 50 is representative of the group of compounds covered by the application, which is being used clinically. The substance is administered in an equal mixture of olive oil, preferably with two per cent anesthesin, added to 55 reduce the pain of injection, although the anesthesin is not required. That is to say, one part of the compound is mixed with an equal part of olive oil, and to this is added a quantity of anesthesin equal to two per cent of 60 the total weight. About five to six cc. of the mixture is injected intramuscularly once a week. However, the administration can be varied substantially, both as to amount and 65 the frequency. The quantities and method of

administration of the other materials mentioned above will be similar.

The scope of the invention should be determined by reference to the appended claims, said claims being construed as broadly as possible consistent with the state of the art. 70

I claim as my invention:

1. As a new bactericidal or bacteriostatic agent, an aliphatic substance containing from 75 10 to 21 carbon atoms and having the general formula

where R and R' represent aliphatic hydrocarbon radicals such as alkyl or alkylene, and where Z represents a hydrogen atom, an alkali or alkaline earth metal or a 85 hydrocarbon radical.

2. As a new bactericidal or bacteriostatic agent, an aliphatic substance containing from 15 to 18 carbon atoms and having the general formula 90

where R and R' represent aliphatic hydrocarbon radicals such as alkyl or alkylene, and where Z represents a hydrogen atom, an alkyl or alkaline earth metal or a 95 hydrocarbon radical.

3. As a new bactericidal or bacteriostatic 100 agent, an aliphatic substance containing from 10 to 21 carbon atoms and having the general formula

where R and R' represent aliphatic hydrocarbon radicals such as alkyl or alkylene, and where Z represents a hydrogen atom, an alkali or alkaline earth metal or a 110 hydrocarbon radical, and where the carboxyl group is attached near the middle of the chain.

4. As a new bactericidal or bacteriostatic agent especially applicable to acid-fast bacteria, a substance which is a member of the group consisting of aliphatic acids, alkali and alkaline earth metal salts thereof and hydrocarbon esters thereof, in which the carboxyl group is located at a point removed from the end of the chain, said substance containing from 10 to 21 carbon atoms. 115

5. A composition as defined in claim 4, and containing from 15 to 18 carbon atoms. 120

6. As a new bactericidal or bacteriostatic agent especially applicable to acid-fast bacteria, a substance which is a member of the group consisting of aliphatic acids, alkali and alkaline earth metal salts thereof, and 125

hydrocarbon esters thereof, in which the carboxyl group is attached to a carbon atom at approximately the center of the chain, said substance containing from 10 to 21 carbon atoms.

5 7. A composition as defined in claim 6, and containing from 15 to 18 carbon atoms.

ROGER ADAMS.
